UNITED STATES PATENT OFFICE.

JNO. J. FIELDS, OF BROOKLYN, NEW YORK.

RAILROAD-CAR SPRING.

Specification of Letters Patent No. 20,998, dated July 27, 1858.

To all whom it may concern:

Be it known that I, JOHN J. FIELDS, of Brooklyn, in the county of Kings and State of New York, have invented and made and 5 have now in use certain new and useful Improvements in Springs for Railroad-Cars and for other Purposes, which I designate as the "Elastic-Cone Socket-Spring;" and I do hereby declare that the following is a 10 full, clear, and exact description of the same, reference being had to the accompanying drawings, making a part of this specification, in which—

Figure 1, is a representation of the spring completed, and detached from the pedestal part of the car frame or truck. Fig. 2, is a vertical section of the spring. Fig. 3, shows the socket, or cup like receptacle part. Fig. 4, represents the hollow elastic cone or 20 sheath part. Fig. 5 shows the inverted cone plunger, or core part. Fig. 6 represents the secondary cone sheath. Fig. 7 represents a secondary inverted cone plunger or solid cone part.

25 The nature of my improvements, consists in constructing a car-spring in such a manner with peculiarly shaped devices, as enables the bringing into requisition an equalization of pressure and compression; where- 30 by the superincumbent weight, or force applied thereon, bears regularly throughout the whole elastic surface employed, vertically, laterally, and obliquely; and diffusing throughout the elastic volume, any force 35 or strain acting thereon.

A most important improved feature pertaining to my spring, is the mode or manner of arranging and applying a greatly diminished quantity or volume of elastic sub- 40 stance, so as to develop an inherent property in an increased degree, and presenting a greater extent of elastic surface, together with a greatly increased resistance or action, over any method heretofore of employing 45 elastic substances for springs.

The better to enable others to be skilled in the construction, application, and use of my improvements, I herewith describe the same.

In Fig. 1, the spring is shown complete, 50 but about one third the dimensions of a large size one. The spring is represented as detached from the pedestal and turned upward; and at *a*, *a*, *a*, *a*, is indicated a suitable metallic socket or cup like receptacle, 55 hollowed out, with slightly tapering walls, or sloping sides as at *b*, *b*, *b*, *b*, about one

third the depth. Thence downwardly, begins a slight fullness, ledge or swell *c*, *c*, *c*, *c*, forming an inverted, cone like hollow, or cavity *d*, *d*, *d*, *d*, the lower termination of which, instead of being acute or pointed, is blunt or spread somewhat as at *e*, *e*, Fig. 2. Conforming to this cone cavity, is used an elastic hollow cone or sheath *f*, *f*, *f*, *f*, Figs. 2 and 4, varying from an inch, or more in 65 thickness, of substance throughout its circumference, and formed at its upper extremity with a rim or increased thickness of substance as at *g*, *g*, *g*, *g*, Figs. 2 and 4. Fitting into this inverted, hollow elastic cone, or 70 sheath, is a regularly formed, inverted cone like plunger, or core plug *h*, *h*, *h*, *h*, formed with an annular disk head or flange part, of suitable thickness. This disk head, or flange part, is concave, or dished somewhat 75 as at *i* and the cone portion is hollowed out, or formed partly with a conical cavity *J*, *J*, *J*, for the insertion if desired of a secondary cone sheath *k*, *k*, *k*, formed with an annular rim *L*, *L*, *L*, into which sheath may 80 be inserted a solid cone plug, or secondary plunger *m*, *m*, *m*, *m*, formed with a solid disk head *n*, *n*, *n*, which is also concave, or dished somewhat as at *o*, *o*, Figs. 2 and 7.

It is well known, that in the use of the 85 best and most approved springs for cars, that a more or less compact, solid mass of rubber is required; or series of disks, varying from six to twenty pounds, in the aggregate, are employed, and such devices or 90 forms of springs, are capable, inherently of sustaining severally, a pressure direct of from one to four tons, and it not infrequently occurs, that under this amount of pressure, that the springs give way, or the 95 elastic mass bursts asunder thus destroying the action of the spring; and it also not unfrequently occurs, where thick masses of rubber are used, that a great portion thereof must possess considerable immobility, or a 100 nonactive property, and the central part of the spring can not give out any elastic action, but be inert, and hence, there must be a more or less loss of the inherent elastic property; and when this is the case, there 105 must ensue therefrom more or less irregular rebound, and vibratory action, causing a rough, thumping, undulatory motion of the car, owing to the inequality of the two forces, pressure and compression.

In the peculiar forms of devices used by me, and the manner of applying the elastic

substance in the form of a hollow elastic cone or sheath, I require but about two pounds, or one third the quantity of elastic substance usually required to sustain a given 5 amount of pressure.

It is found by actual practical test, that every particle of the elastic property is brought into use, in the application of my improvements, for the sloping sides on the 10 conical wall d, d, d, d , of the cup or socket a, a, a, a , acts as a surrounding shield, and pressing upward, against the oblique, or conical surface of the rubber f, f, g, g , every particle of the substance thereof is equally 15 supported, an equalization of the elastic force, and a regular diffusion of pressure, and compression produced throughout the entire thickness of the substance used.

I am well aware, that in a patent granted 20 to Fowler M. Ray October 8th 1850, forms of india rubber and metal are shown, and termed "frustums of hollow cones." But said forms in reality are not what they are claimed to be, either in shape, or principle; 25 but are on the contrary, obliquely cut concave sections of a cylinder, and possess two vertical parallel sides c, c, c, c Fig. 9 of equal extent, and two parallel oblique surfaces d, d, d, d , also of equal extent; and 30 these forms of Ray's are pierced through and through as at $c^2 c^2 c^2$ Fig. 9; then again, their elastic or yielding action is in a direct vertical line only; and the resultant, force thereof, is the action laterally, or at right 35 angles from a vertical line; ensuing from the downward pressure, producing the compression which compression distends the elastic substance outwardly right and left as shown by the dots Fig. 9. But observe, 40 that in the use of my devices, I bring into requisition, and apply in a peculiar manner the principle of a true cone, which necessarily enables me to use a greatly reduced amount of elastic substance; affording as 45 great a resisting energy as is developed in four times the amount of rubber ordinarily applied as a spring, and the yielding action afforded by my spring, is not over one fourth of an inch in play; consequently the 50 motion must be smooth, uniform, and without any rebound with little, if any friction.

The better to demonstrate the difference between my spring, and the spring of Fowler M. Ray, a reference must be had to the 55 demonstrative diagram 8, where a true cone is represented inverted and the sides ab, ab, ab, ab , tend inwardly from the base of the cone, instead of diverging outwardly as do the oblique surfaces d, d, d, d , of Ray's 60 forms as shown in the demonstrative diagram 9. And while the compression in Ray's spring is in an outwardly horizontal direction from the center of pressure indicated by the arrows d^2, d^2 , diagram 9, 65 the compression in my spring is inwardly,

and upwardly simultaneously in the direction of the arrows e, e, e and the dots f, f , diagram 8; and thus the resultant force of my spring, is that force, ensuing from the compression, through the coming together 70 simultaneously of the inwardly sloping surfaces $ab-ab-ab-ab$ —diagram 8; and instead of diminishing, or destroying the elastic energy, it is increased, by affording, or engendering, a self sustaining principle 75 through the agency of the upward pressing of the surrounding shell, or encompassing cup receptacle a, a, a, a , Figs. 1, 2, 3, and this resultant force of my spring terminates in the lifting up, and swelling out as at the 80 dots f, f , diagram 8, thereby affording a self sustaining action, instead of distending, or expanding outwardly and thereby necessarily diminishing the elastic property as is the case in the operation of Fowler M. Ray's 85 spring.

From the peculiar forms of devices and the manner of applying the elastic substance in my spring, there is barely a possibility 90 of their becoming useless by any natural wear, or abrasion of the parts; and owing to the great simplicity of my springs, they can be most readily applied to any car truck, in use, without altering or rearranging any portion of the pedestal, or running 95 gear. And, should there be any accident beyond the natural wear and tear, any injured or defective part of the spring can be replaced instantly by substituting new parts, at a mere nominal cost; and all such 100 combinations and appliances as rings, disks, bands, tubes, and central bolts, or rods, are dispensed with entirely; and thus the cost of car springs is diminished at least fifty 105 per cent; while at the same time is afforded 110 not merely a simply constructed, but a most effectually operating secure spring.

In the application of my springs, they can be used, reversed, or inverted in position as well as in the position shown in the dia- 110 grams.

The secondary parts shown in Figs. 6 and 7, are only designed to be used when a greater yielding motion is desired.

Having shown the form of construction 115 of my spring, and described the nature, principle, application and great utility thereof, and disclaiming the mere application of elastic substances for springs, as well as disclaiming in full the invention use or application of the perforated concave devices or forms described and claimed by Fowler M. Ray, and by him designated "frustums of hollow cones" with central 120 rod.

What I claim however, as new, and desire to secure by Letters Patent of the United States, is as follows:

I claim the cup or receptacle a, a, a, a , formed with the larger cavity b, b, b , the 130

swell or ledge *c, c, c*— the sloping or conical cavity *d, d, d, e, e, e*— the elastic, hollow cone, or sheath *f, f, g, g*, the inverted cone plunger or core part *h, h—i, i*,— through 5 all of which, the whole elastic principle or property of the material or substance used, is brought into requisition, and the pressure

or weight applied, is equalized, or diffused throughout the substance employed, substantially as herein set forth and described. 10

JOHN J. FIELDS. [L.S.]
